UNITED STATES PATENT OFFICE.

SAMUEL CLARKE, OF CHILD'S HILL WORKS, COUNTY OF MIDDLESEX,
ENGLAND.

DESIGN FOR A LAMP.

SPECIFICATION forming part of Design No. 18,378, dated June 12, 1888.

Application filed March 6, 1888. Serial No. 266,351. Term of patent 11 years.

To all whom it may concern:

Be it known that I, SAMUEL CLARKE, of Child's Hill Works, in the county of Middlesex, England, a subject of the Queen of Great Britain, have invented and produced a new and original Design for a Lamp, of which the following is a specification, reference being had to the accompanying drawings, forming part thereof.

- 10 The main features of my design are a boat-shaped lamp body resting on a circular central molded base, with ornamental scallops around the sides of the body and a rounded raised central flange on the deck or cover, in which rests an open topped dome-shaped cover.
- 15 Figure 1 is a side elevation, and Fig. 2 a plan.

The lamp is of the class known as "Fairy lamps."

- 20 The drawings show the lamp as consisting of a boat-shaped body, *a*, resting on a circular

central molded base, *d*, and provided with an ornamental handle, *e*, a flange or ring, *b*, with a rounded base, which surrounds a central opening in the top of the lamp, and an open-topped dome-shaped cover, *c*, resting on the top of the cover inside the flange, the dome being of glass or other transparent or translucent material.

I claim—

The design for a lamp herein shown and described, consisting of a boat-shaped body resting on an ornamental base, its ornamental handle, ornamental sides, the central flange, and the dome resting thereon.

SAMUEL CLARKE.
